UNITED STATES PATENT OFFICE.

AARON HIRSCHWITZ, OF NEW ORLEANS, LOUISIANA.

MINIATURE-COTTON-BALE BOX.

1,357,866.

Specification of Letters Patent. Patented Nov. 2, 1920.

Application filed February 27, 1920. Serial No. 361,775.

To all whom it may concern:

Be it known that I, AARON HIRSCHWITZ, a citizen of the United States, residing at New Orleans, in the parish of Orleans and 5 State of Louisiana, have invented certain new and useful Improvements in Miniature-Cotton-Bale Boxes; and I do hereby declare the following to be a full, clear, and exact 10 description of the invention, such as will enable others skilled in the art to which it appertains to make and use the same.

The present invention relates to improvements in miniature cotton bale boxes, and has for an object to provide a small box 15 made in imitation of a miniature cotton bale forming a souvenir.

Another object of the present invention is to improve the construction of souvenir boxes of this kind and to strengthen the 20 construction thereof.

A further object of the invention resides in providing a simple and inexpensive construction made to accurately resemble a cotton bale in miniature and adapted to retain 25 the shape of the bale against shocks and jars incident to transportation and use.

In the accompanying drawings forming a part of this application, and in which similar reference symbols indicate corresponding 30 parts in the several views:

Figure 1 is a perspective view of an improved miniature cotton bale box constructed according to the present invention.

Fig. 2 is a horizontal sectional view taken 35 on the line 2—2 in Fig. 1.

Fig. 3 is a transverse sectional view taken on the line 3—3 in Fig. 2.

Fig. 4 is a fragmentary perspective view 40 of the improved box with parts thereof broken away to show the construction; and

Fig. 5 is a perspective view of the drawer or tray.

Referring more particularly to the drawings, 1 designates a tube of cardboard, or 45 other suitable material, preferably made rectangular in cross section for purposes of increased strength over cylindrical or oval cross sections, and having one end thereof open as shown in Fig. 4. A wall 2 closes 50 the other end of the tube 1.

Within the tube 1 is slidably and removably fitted a liner 3, also of substantially rectangular form in cross section, and adapted to be snugly received in the tube 1 55 and frictionally held therein against accidental displacement, although being capable

of withdrawal therefrom when suitable pressure is exerted to this end.

A drawer or tray 4 of the usual box-like character employed in slide boxes is provided of a size to slip within the liner 3 and to slide back and forth therein with a degree of friction suitable for holding the tray or drawer 4 in the closed position shown in Figs. 1 and 2, without the aid of other devices or fastening means. The drawer or tray 4 will be found useful for holding candy or other goods suitable for selling in a souvenir of this character.

In order to lend character to the souvenir 70 that it may the more faithfully represent a bale of cotton in miniature, and at the same time be useful for purposes of additional strength, side pasteboards 5 are employed in connection with the sides of the tube 1. The 75 pasteboards 5 are of substantially the same size as the sides of the tube 1 except that the pasteboards are preferably of slightly increased height to admit of bending the same to a curved form substantially as shown in 80 Figs. 3 and 4, and at the same time bringing the upper and lower horizontal edges of the pasteboards 5 and side walls of the tube 1 into alinement.

The bulged out central portions of the 85 pasteboards 5 are reinforced and connected to the sides of the tube 1 by means of a suitable number of strips 6, which may also be of pasteboard or some other appropriate material, and which are glued or otherwise 90 secured to each other. The innermost strips 6 are also glued or otherwise affixed to the central longitudinal outer portions of the walls of the tube, and the pasteboards 5 are glued to the outermost of the strips. In the 95 form shown in the drawings, three such strips 6 are employed, but it will be obvious that a greater or less number may be used, accordingly as it is desired to increase or decrease the bulged effect of the pasteboards 5. 100 The pasteboards 5 need no other securing than that to the outermost of the strips 6, but if preferred the edges thereof may be clamped or otherwise affixed to the adjacent parts of the tube 1.

Cotton or other suitable stuffing 7 is placed against the top and bottom of the tube 1, and similar stuffing 8 is placed on the outside of the pasteboards 5. Burlap or other suitable textile material 9 is employed 110 in which to wrap the tube 1 and cover the closed end 2 thereof, and ties 10 are used to

go about the burlap 9 and the cotton so as to hold all of these various parts tightly about the straight walls of the tube 1 and at the same time confine the edges of the pasteboards 5 closely against the adjacent edges of the said walls of the tube.

The sides of the souvenir package are bulged out or rounded in a manner to partake accurately and faithfully of the character of a bale of cotton, and the presence of the curved pasteboards 5 will preserve this rounded contour of the burlap at the sides of the package, the pasteboards 5 being in turn reinforced by the strips 6. This side construction will therefore be found to be exceedingly strong and durable, yet inexpensive to construct and simple to make; and it will also receive the shocks and jars incident to transportation and use which would otherwise devolve directly on the side walls of the tube 1 and be apt to stave the same in.

The burlap at the open end of the tube 1 is turned in between such tube and the adjacent portions of the liner 3, as indicated at 11 in Fig. 4. The free edge of the burlap 11 may be simply allowed to project across the open end of the tube 1 prior to inserting the liner 3, and when such liner 30 is moved in place it will push the free end 11 of the overlap into the position it is shown occupying in Fig. 4.

The tray or drawer 4 is provided with a tab 12, also preferably made of burlap, and having an elongated portion 13 clamped or otherwise secured beneath the bottom of such tray or drawer. The tab 12 provides a convenient means which may be caught between the thumb and forefinger for drawing the tray 4 out of the liner 3.

The front wall of the tray or drawer is also preferably faced with burlap sheets 14 and 15 which overlap centrally and have their edges projecting beyond the side walls of the drawer or tray, so that they may conceal the front edges of the same and the edges of the liner 3.

It is obvious that those skilled in the art 50 may vary the details of construction and arrangements of parts without departing from the spirit of my invention, and therefore I do not wish to be limited to such features except as may be required by the 55 claims.

I claim:

1. A miniature cotton bale box comprising a tube of substantially rectangular cross section, a liner removably mounted in the tube, a drawer or tray slidably mounted in said liner, curved side pieces placed along the sides of said tube, a textile material placed about said tube, means for holding the textile material in place, and a stuffing placed between the textile material and the curved side pieces, substantially as described.

2. An improved miniature cotton bale box comprising a tube of substantially rectangular cross section, a box tray slidably within the tube, strips secured together and to the central longitudinal exterior portions of the side walls of the tube, pasteboards secured to the outermost of the strips and bent to a curved form, cotton placed about said curved pasteboards and the upper and lower walls of the tube, and burlap inclosing the cotton along the sides and exposing the same at the bottom and top of the tube, ties going about the burlap and cotton to hold the same in place, substantially as described.

3. A cotton bale box comprising a tube of substantially rectangular construction having one end thereof closed, a liner frictionally and removably fitted in said tube, a box tray slidably mounted in said liner and having a burlap tab thereon for withdrawing the box, a pair of overlapped sheets of burlap secured to the front wall of the box and extending beyond the front edges thereof, a series of elongated narrow strips secured together and to the longitudinal central portions of the side walls of the tube, curved pasteboards secured to the outermost of the strips and having their free edges lying against the upper and lower edges, respectively, of the sides of the tube, cotton placed about the pasteboards and upper and lower walls of the tube, burlap secured about the side pasteboards and partially about the upper and lower portions of the tube but allowing the cotton to show therethrough, ties passing about the burlap and cotton, the burlap extending about the closed end of the tube, the free edge of the burlap at the open end of the tube being folded between the tube liner, substantially as described.

AARON HIRSCHWITZ.
